US0D1036698S

(12) **United States Design Patent** (10) **Patent No.:** **US D1,036,698 S**
(45) **Date of Patent:** **** Jul. 23, 2024**

(54) **SAMPLE RACK ADAPTER**

(71) Applicant: **BECTON, DICKINSON AND COMPANY**, Franklin Lakes, NJ (US)

(72) Inventor: **Alyssa Shedlosky**, Reisterstown, MD (US)

(73) Assignee: **BECTON, DICKINSON AND COMPANY**, Franklin Lakes, NJ (US)

(**) Term: **15 Years**

(21) Appl. No.: **29/894,552**

(22) Filed: **Jun. 12, 2023**

Related U.S. Application Data

(62) Division of application No. 29/802,903, filed on Aug. 9, 2021, now Pat. No. Des. 993,445.

(57) **CLAIM**

The ornamental design for a sample rack adapter, as shown and described.

DESCRIPTION

FIG. 1 is a perspective view of a sample rack adapter showing my new design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a bottom view thereof; and,

FIG. 9 is a perspective view of a sample rack adapter according to my design placed in a sample rack which is not part of the design.

The broken lines in FIGS. 1-8 depict portions of the sample rack adapter that form no part of the claimed design. The additional broken lines in FIG. 9 depict environmental subject matter that form no part of the claimed designs.

1 Claim, 9 Drawing Sheets
